UNITED STATES PATENT OFFICE

CHARLES R. KEISER, OF DAYTON, OHIO, ASSIGNOR TO THE SERTON RUBBER COMPANY,
OF DAYTON, OHIO, A CORPORATION OF OHIO

SUPPORT FOR COLLAPSIBLE TUBES

Application filed July 13, 1931. Serial No. 550,348.

This invention relates to improvements in means and method of supporting collapsible tubes, and has for its object to provide a support for a tube adapted to contain paste, muscilage, glue and other adhesives.

5 It is particularly the object of this invention to provide a cardboard support having parts struckup thereon for supporting one end of a tube for containing any of the above materials.

10 It is also an object of this invention to provide, in connection with a cardboard support, a scraper for removing dirt and foreign materials from the surface to which the contents of the tube are to be applied, and applying this scraper to the cardboard in such a manner that it will assist in supporting the tube containing the material, preventing its lateral and vertical movement, and prevent the tube being crushed.

15 It is my object to eliminate all forms of glued strips and other similar means to support the tube on the card.

20 These and other advantages will appear from the following description taken in connection with the drawing.

25 Referring to the drawing:

Figure 1 is a side elevation of a piece of cardboard showing the manner in which a 30 tube of some material is supported thereon.

Figure 2 is a top plan view of the parts as shown in Figure 1.

Figure 3 is a bottom plan view of the parts as shown in Figure 1.

35 Figure 4 is a section on the line 4-4 of Figure 1.

Figure 5 is a side elevation similar to Figure 1, but showing protective cardboard used in connection with the scraper plate for protecting the end of the tube.

40 Figure 6 is a section on the line 6-6 of Figure 5.

The numeral 1 is used to designate a piece of cardboard suitably shaped and formed to 45 constitute a support for a tube of muscilage,

paste or other adhesive. This piece of cardboard is rectangular in shape, and may for convenience be termed a card, which has struckup adjacent one end a loop member 2 forming an arch-shaped slot around a 50 tongue 3.

Near the other end of the card is a loop 4 formed by two transverse slits 5 and 6, the slit 5 being longer than the slit 6. The purpose of these two slits is to form slots 55 through which a scraper in the shape of a disc may extend for supporting one end of a tube 7. On the upper end of this tube, as shown in Figure 1, is a neck 8 adapted to receive a cap or closure 9 for concealing the 60 contents of the tube. The end of the tube away from the neck is closed by means of a loop 10, such as is usually found in connection with tubes of cream and the like. The scraper plate or disc, which is circular in 65 shape, is indicated by the numeral 11 and extends through the slits 5 and 6, as shown in Figure 1, for supporting the lower end of the tube.

The part 11 of the disc extending through the slits and supported between the body of the card and the part 4 is slightly more than one-half of the scraper. The upper or smaller part of the scraper or disc is bent at right angles to the lower or larger part, as indicated by the numeral 12, and constitutes a support for one end of the tube. Extending through the part 12 is a slot 13, which receives the part 10 of the tube for holding the tube 75 in place on the card.

80 Whenever it is desired to place the tube on the card the looped lower end is placed through the slot 13 and the loop 2 is placed over the neck of the tube and fastened thereto by means of the cap or closure 9. If necessary the cap may be removed in order to properly place and locate the loop 2. Thereafter the cap is replaced so that the upper end of the tube is securely held by means of the loop. 85 90

In order to protect the part 10 of the tube against wear or being cut by the part 12 of the scraper, a protector 14 may be provided and placed on top of the part 12 between this part 12 and the lower end of the tube. This protector is made of cardboard and is of the same size and shape as the part 12 of the scraper and has a slot therein in alignment with the slot 13 through which the looped end of the tube passes, as clearly shown in Figure 4. However, the protector is not shown in this figure.

While the present card shows only one tube, a plurality of tubes may be arranged on each card and so arranged that the cards may be packed one upon the other with the scrapers on one card at one end of the tubes and the scrapers on the other card at the other end of the tubes. By this means the parts 12 hold the cards in spaced relation so that the tubes cannot be easily crushed or mashed. In packing the tubes may be arranged in staggered relation to each other so that the least possible space will be occupied by the cards thus assembled.

I desire to comprehend within my invention such modifications as may be embraced within my claims and the scope of my invention.

Having thus fully described my invention, what I claim as new and desire to secure by Letters Patent, is:

1. A paste tube support consisting of a piece of cardboard having a loop cut therefrom to engage the neck of the tube and slits spaced from the loop, and an insert in the slits in the cardboard having a right-angularly extending part to support the closed end of the tube.

2. A paste tube support consisting of a piece of cardboard having a loop cut therefrom to engage the neck of the tube, and an insert in the cardboard to support the closed end of the tube, said insert consisting of an outwardly projecting member having a slot therein to receive a loop on the closed end of the tube.

3. A paste tube support consisting of a piece of cardboard having an integral loop member extending from one end thereof to engage the mouth end of the tube, and a slotted projection from the other end to support the closed end of the tube, a part of said tube projecting within said slot.

4. In a support for paste tubes, a piece of cardboard having a loop member cut therefrom to engage one end of the tube, and a scraper member supported by the cardboard and having a part extending therefrom, said extending part having a slot therein to receive a part of the other end of the tube.

5. In a support for a paste tube having a neck end closure at one end and a crimped part at the other end, a board member having a loop cut therefrom to fit around the neck,

said board member having slits therein, and a scraper having a portion inserted into said slits and another portion bent away from the board and having a slot therein to receive the crimped part of the tube.

6. In a support for a paste tube having a neck at one end and a crimped part at the other end, a piece of sheet material having a loop member cut up therefrom to engage said neck, said piece of sheet material having slits therein, and a circular scraper in said slits, a portion of said scraper being bent away from the other portion to form a tube support, said bent-away portion having a slot therein to receive the crimped part of the tube.

7. In a support for a paste tube having a neck at one end and a crimped part at the other end, a piece of sheet material having a loop member cut up therefrom to engage the neck, and a slotted bench-like projection from said piece of sheet material to support the crimped end of the tube with the crimped part in the slot.

8. In a support for a paste tube having a neck at one end and a crimped part at the other end, a piece of cardboard having means integral therewith to engage said neck, and a metal scraper attached to the cardboard and extending therefrom to support the crimped end of the tube, said scraper having a slot therein to receive the crimped part of the tube.

9. In a support for paste tubes, a cardboard having integral means to engage one end of each tube, and a metal disc for each integral means attached along one portion thereof to the cardboard and having another outwardly extending portion to support the other end of a tube, said outwardly extending portion having a slot to receive a part of the tube end.

10. A support for paste tubes consisting of a card having integral loops to hold one end of the tubes, a removable metal scraper member for each loop mounted on the card to support the other ends of the tubes, and a protector between each tube and its scraper member.

11. A support for paste tubes consisting of a card having integral loops to hold one end of the tubes, a removable metal scraper member for each loop mounted on the card to support the other ends of the tubes, and a fibrous protector between each tube and its scraper member.

12. A support for paste tubes consisting of a card having an integral loop cut therefrom to hold one end of a tube, a removable metal disc-shaped scraper cooperating with the loop mounted on the card to support the other end of the tube, and a protector between the tube and its scraper, the scraper and its protector having a slot therein to receive a part of the tube.

13. A support for paste tubes consisting of

• a card having an integral loop cut therefrom
to hold one end of a tube, a removable metal
disc-shaped scraper cooperating with the
loop mounted on the card to support the
other end of the tube, and a cardboard pro-
tector between the tube and its scraper, the
scraper and its protector having a slot there-
in to receive a part of the tube.

5 In testimony whereof, I affix my signature.

10 CHARLES R. KEISER.
